CLAIM

The ornamental design for an enclosed hexagonal foam seating furniture with removable round partition, as shown and described.

DESCRIPTION

FIG. 1 is a perspective view of an enclosed hexagonal seating furniture with a removable round partition positioned within the furniture in accordance with the present invention with a side seam and a bottom base board with legs shown in broken lines;

FIG. 2 is a front face view of the enclosed hexagonal seating furniture of FIG. 1;

FIG. 3 is a top-side view of the enclosed hexagonal seating furniture of FIG. 1;

FIG. 4 is a right-side view of the enclosed hexagonal seating furniture of FIG. 1;

FIG. 5 is a left-side view of the enclosed hexagonal seating furniture of FIG. 1;

FIG. 6 is a rear face view of the enclosed hexagonal seating furniture of FIG. 1;

FIG. 7 is a bottom view of the enclosed hexagonal seating furniture of FIG. 1; and,

FIG. 8 is a perspective view of the enclosed hexagonal seating furniture of FIG. 1 with the round partition removed from the furniture.

The broken lines shown in the Figures are for environmental purposes only and form no part of the claimed design.
